UNITED STATES PATENT OFFICE.

FRANK E. HERDMAN, OF INDIANAPOLIS, INDIANA.

ELECTRIC-MOTOR-CONTROLLING APPARATUS.

SPECIFICATION forming part of Letters Patent No. 519,124, dated May 1, 1894.

Application filed October 20, 1892. Renewed January 11, 1894. Serial No. 496,550. (No model.)

To all whom it may concern.

Be it known that I, FRANK E. HERDMAN, a citizen of the United States, residing at Indianapolis, county of Marion, and State of Indiana, have invented a new and useful Improvement in Electric-Motor-Controlling Apparatus, of which the following is a full, clear, and exact description, reference being had to the accompanying drawings, which form a part of this specification.

My invention relates specifically to the combination and arrangement of devices whereby the admission of the current to the motor is controlled.

15 In the accompanying drawings Figure 1 represents a side elevation of my apparatus, sufficient to disclose my invention. Fig. 2 is a diagrammatic view showing the direction of the various circuits.

20 M is the motor provided with the shaft m, for the transmission of power, the field of the motor being in direct electrical connection with the source of current supply through binding posts 4 and 3, and the armature of

25 the motor being in electrical connection with binding post 5, which is in electrical connection with brush 8 of the switch, I, the switch, I, being in electrical connection with both poles of current supply; and the resistances

30 R are in electrical connection with brush 7 of switch, I, and said resistances, through arm, J, are in connection with the armature of the motor.

G is the operating arm for the switch, I.

35 U is a double pole switch, the contacts 17 and 18 of which are in electrical connection with the source of current supply. To the arm J is attached the core of a solenoid, 25, and dash pot, 26. The solenoid is in elec-

40 trical connection with the contacts, U' and U² of switch U. In the electrical connection between contact, U' and the solenoid is the contact, 27, in contact with brush, 28. The electrical connection between arm J and the

45 binding post 6 (by which resistances are connected with the armature of the motor) has in its circuit the solenoid 29, the core of which carries the brush 28. The dash pot 26 has a packed cylinder, 100, containing oil or other

50 liquid or gas and has a pipe connection, 101, from its upper side to its lower side, so as to

allow the contents to pass from one side to the other of the piston.

To the bottom of the dash pot are connected

two pipes, 102 and 103, one carrying the check 55

valve 30 and the other carrying the small

cock 31. In the main pipe, 104, to which

these converge and which extends from one

side of the piston to the other, is cock 32, and

also cock, 33. It is desirable that when the 60

current is cut off from the motor the arm J,

should travel back over the resistances rap-

idly, and to accomplish this the oil must rap-

idly pass from the upper side of the piston

to the under side, and to permit this, the 65

check valve, 30, opens upward so that while

arm J is returning it opens, allowing the oil

rapidly to enter below the piston. The speed

at which the oil passes can be controlled by

means of the adjusting cock 32. As the pas-

sage of the arm, J, over the resistances,

when the current is admitted, is desired to be

slow, the passage of the oil from beneath the

piston of the dash pot to the upper side

must be slow. To accomplish this the check 70

valve, 30, closes, and the cock 31 can be ad-

justed to control as desired. Link 125 con-

ncts cock 33 with the lever T, which lever is

in connection with the operative mechanism.

Cock 33 is so adjusted that when the lever T 75

is in its central position this cock is closed.

Either throw of the lever T from the center

opens this cock. If the lever T be operated so

that its switch connecting end is lowered, the

switch U is brought in contact with contacts 80

U' and U² and at the same time the cock 33

is opened. The circuit is now closed through

the solenoid 25, which causes it to act forcing

the arm over the resistances against the dash

pot 26, and the speed of the movement of arm 90

J is regulated by the adjustment of cock 31.

When the lever T is operated to bring switch

U to a central position, breaking the circuit

with contacts U' U² thereby breaking the cir-

cuit of the solenoid 25,—the same movement 95

of lever T brings the cock 33 to a central po-

sition. When in this position the oil located

in the dash pot is prevented from passing to

one side or the other, and the arm J is held

in a fixed position. If the lever T be moved 100

further the cock 33 is operated, but in the

opposite direction from that when the switch

is in contact with the contacts, U' and U². When open in this direction, the weight of the solenoid core draws the lever J back, the speed at which it is drawn back being governed by 5 the speed at which the liquid in the dash pot is permitted to pass from one side to the other. In case the current passing through the main circuit becomes excessive and beyond what should be permitted to enter the motor, the 10 weight of the core of the solenoid 29 is so adjusted that the strength of the solenoid at this time would become such as to draw said core, in thus drawing brush 28 off of contact with contact 27 and breaking the electrical circuit through the solenoid 25 and at 15 the same time opening cock 34 to which said core is connected by lever 126, link 127 and bell crank 128, allowing the oil to pass freely from one side to the other of the dash pot. 20 By this arrangement, if for any reason the current in the motor becomes too great the current is automatically cut off from the motor, thereby preventing damage to the motor. Under such conditions when the arm J is re- 25 turned the current would be broken through the solenoid 29, thereby permitting the core to return, closing the circuit through the solenoid 25, which would again act and throw the arm J over the resistance contacts the 30 same as before, so that as long as the lever is kept off of the center, and the current is too great for the armature this movement will be kept up. To obviate this to the operating bar G is attached an inclined plane 35, and 35 upon this inclined plane rests a roller 40 having a lever 36 pivoted at 37, the bar end of this lever 36 coming in contact with projection 38 upon the core of the solenoid 29. When the solenoid 29 is operated and core 40 drawn, the lever 36 would rise behind the projection 38 and thereby prevent the return of the core, and in consequence the circuit could not be again closed through the solenoid 25 until the operating bar G had been 45 brought to the center (at which time the current will be cut out of the armature circuit) which would cause the active end of lever 36 to rise, freeing the projection 38 from said lever.

Having now fully described my invention, 50 what I claim, and desire to protect by Letters Patent, is—

1. The combination with a source of current supply, and an electric motor of an armature current controlling switch, resistances 55 in circuit with said switch, an arm in circuit with the armature of the motor and adapted to travel over said resistances, a solenoid, the core of which is connected to said arm, an independent solenoid controlling switch, electric connection between said switch and current supply and between said switch and solenoid and independent operating devices for each of said switches.

2. The combination with a source of current supply and an electric motor of an armature circuit controlling switch, resistances 60 in circuit with said switch, an arm adapted to

travel over said resistances, electric connection between said arm and armature of motor, a solenoid through which said connection 70 passes, the core of said solenoid carrying a brush, a solenoid the core of which is connected with said resistance arm, a solenoid controlling switch, electric connection between said switch and a contact as 27, and 75 electrical connection between said solenoid and brush 28 carried by first mentioned solenoid core.

3. The combination with a source of current supply, and electric motor, a resistance 80 interposed between the armature of the motor and source of current supply, a resistance arm in electric connection with said resistance and with said armature of the motor, a solenoid the core of which is connected with 85 said arm, electrical connection between said solenoid and the source of current supply, a dash pot, the piston of which is connected with said resistance arm, a cylinder for said piston adapted to receive and contain a fluid 90 and pipes leading from the lower to the upper portion of said cylinder.

4. The combination with a source of current supply, an electric motor, resistances interposed between the armature of the motor 95 and source of current supply, a resistance arm in electrical connection with said resistance and with said armature of the motor, a solenoid the core of which is connected with said arm, electrical connection between said 100 solenoid and the source of current supply, a dash pot, the piston of which is connected with said resistance arm, a cylinder for said piston adapted to receive and contain a fluid, a pipe leading from the upper to the lower 105 portion of said cylinder, said pipe terminating in two branch pipes, cocks on said pipes, a cock on the main pipe and the controlling cock on the main pipe also.

5. The combination with a source of current supply and an electric motor of an armature current controlling switch, resistances in circuit with said switch, an arm in circuit with the armature of the motor and adapted to travel over said resistances, a solenoid the 110 core of which is connected to said arm, an independent solenoid controlling switch, electric connection between said switch and current supply and between said switch and solenoid and independent operating devices for 115 each of said switches, a dash pot connected to said resistance arm, a cylinder adapted to hold liquid, a pipe leading from the upper to the lower portion of said cylinder, a cock on said pipe, connection between said cock and the solenoid controlling the switch operating device.

6. The combination with a source of current supply and an electric motor of an armature circuit controlling switch, resistances 120 in circuit with said switch, an arm adapted to travel over said resistances, in circuit with said switch, an arm adapted to travel over said resistances, electric connection be- 125

tween said arm and armature of motor, a solenoid through which said connection passes, the core of said solenoid carrying a brush, a solenoid, the core of which is connected 5 with said resistance arm, a solenoid controlling switch electric connection between said switch and a contact as 27, and electrical connection between said solenoid and brush 28 carried by first mentioned solenoid core, 10 a dash pot, the piston of which is connected to the resistance arm, a cylinder adapted to contain liquid, a pipe connecting the bottom and top of said cylinder, a valve in said pipe, a lever connected to the core of the first mentioned solenoid and intermediate connection 15 between said lever and said valve.

7. The combination with a source of current supply and an electric motor of an armature circuit controlling switch, resistances 20 in circuit with said switch, an arm adapted to travel over said resistances, electric con-

nection between said arm and armature of motor, a solenoid through which said connection passes, the core of said solenoid carrying a brush, a solenoid the core of which is connected with said resistance arm, a solenoid controlling switch, electric connection between said switch and a contact as 27, and electrical connection between said solenoid and brush 28 carried by first mentioned solenoid core, 25 an operating bar for operating the armature controlling switch, an inclined plane as 35, attached to said bar said inclined plane having a lever pivoted to a projection on the core of the first mentioned solenoid in 30 line with the end of said lever.

In testimony of which invention I have hereunto set my hand.
